UNITED STATES PATENT OFFICE.

ALICE P. McCCLAIR, OF ATLANTA, GEORGIA.

REVOLVING WINDOW-FRAME.

1,346,663.

Specification of Letters Patent. Patented July 13, 1920.

Application filed March 14, 1919. Serial No. 282,606.

To all whom it may concern:

Be it known that I, ALICE P. McCCLAIR, a citizen of the United States of America, residing at Atlanta, in the county of Fulton 5 and State of Georgia, have invented new and useful Improvements in Revolving Window-Frames, of which the following is a specification.

The purpose of the invention is to provide a new and improved construction of window frame so supported with the frame that it may be turned around to bring that side which is normally outside into such a position that the panes in the frame may 15 readily have their outside faces cleaned from within the room. The improved frame is also useful as a means for opening a window of which it is a part so that the benefit of the full window opening may be had for 20 ventilation in times of warm weather.

A further purpose of the invention is the provision of a device of this character which is simple in construction, durable and effective in operation and inexpensive to 25 manufacture and apply.

Other and further objects appear in the following description, wherein the invention is set forth in detail.

To the exact construction in which it is 30 shown and described, the invention is not to be restricted. The right is reserved to make such changes or alterations as the actual reduction to practice may suggest, in so far as such changes or alterations are compatible in spirit with the annexed claim.

In the accompanying drawings:

Figure 1 is a front elevational view of the improved window frame.

Fig. 2 is a section on the line 2—2 of 40 Fig. 1.

Fig. 3 is a section on the line 3—3 of Fig. 1.

Fig. 4 is a detailed perspective view showing a portion of the frame and the pivot 45 stud therefor.

Fig. 5 is a detailed elevational view showing one of the slides by means of which the frame is secured in its normal position.

To carry the invention into effect there is 50 provided a main frame 1 for the window opening, this frame having the usual vertical stiles and resting upon the sill 2.

A transverse plate member 3 is attached on the inner or underface of the top of the 55 frame 1, and set centrally both as respects

the length and width of this plate there is a socket member 4, this socket member being set in the plate so that its bottom lies flush with the bottom face of the plate. Set in the sill 2 and directly below the socket 4 there is a 60 second socket 5 and these two sockets are designed to receive the studs 6 which project from and are formed with plates 7, the latter being set in the top and bottom edges of a supplemental frame 8, the latter being 65 formed with appropriate beads 9 so that it may receive the sash 10, this supplemental frame being pocketed on its sides for the reception of the sash controlling means, which may be either weights connected with the 70 sash by appropriate chains or ropes, or spring operated rollers as indicated at 11 which are connected to the sash by appropriate chains as indicated at 12. Any appropriate means of mounting the sash may 75 be employed, such means being no part of the present invention, and hence needless of detailed description here.

By virtue of the studs 6, however, the supplemental frame 8 which carries a sash may 80 be rotated in the main frame 1 to bring those sides of the sash normally outside to a position where they stand facing the inside of the room. The sash may thus be easily cleaned when the supplemental frame 8 is 85 turned around.

In the normal position of the supplemental frame, however, means are provided for locking it in such a position as well as for keeping out drafts through the cracks 90 existing between it and the main frame thereto, and to this end there is attached to the underface of the top of the main frame a plate 13 which is secured to the main frame by means of the hinges 14, this plate 95 normally lying against the inner edge of the plate 3 and against the inside face of the supplemental frame at the top thereof. Likewise, at the bottom ends a second plate, this plate generally designated 15 is secured 100 to the sill 2 by means of the hinges 16 and this plate, therefore, may swing over to have its under face lie on top of the sill with its edge against the inner face of the supplemental frame 8 at the bottom thereof. The 105 plate 15 may also be swung back away from the sill at which time its under face is brought into a plane parallel to a plane of the top face of the sill, in which position of the plate 15 the supplemental frame 8 may 110

be turned around, such movement of the frame 8 causing the plate 13 to be swung back toward a horizontal position to permit the frame 8 to pass. When the plate 15, however, is turned over to bring its edge against the inner face of the frame 8 turning movement of the latter is precluded.

In addition to providing the plate 15 to secure the frame 8 against movement, means are provided for further securing the frame 8 against movement at the side edges and this latter means also precludes the entrance of draft at the side edges the said means including plates 17 formed with diagonally disposed transverse slots 18 through which headed studs 19 pass to secure the plates 17 to the frame 8. Obviously, this construction provides for lateral movement of the plates 17 and they may be moved laterally to engage in slots formed in the sides of the main frame 1, or moved laterally in the reverse direction to disengage them from the said slots, so that when the plate 15 is turned as aforesaid, the supplemental frame 8 may be turned freely. The transverse slots 18 are disposed so that when the plates 17 are moved laterally they are likewise moved upwardly and combined clamping screws and handles 20 are threadingly mounted in these plates so that they may be easily moved by hand, and clamped in the positions to which they are moved, the tightening of the clamping screws 20 serving to

seat them against the inner face of the frame 8, to hold the plates 17 in any position to which they may be moved.

From the foregoing description and the accompanying drawings, it is believed that a clear enough understanding of the invention is to be had to render further description unnecessary.

The invention having been described, what is claimed as new and useful is:

A revolving window frame comprising a main frame, a supplemental frame support on vertical pivots for turning movements in the main frame, a plate swingingly mounted at the top of the main frame and gravity actuated to lie against the window face of the supplemental frame at the upper end thereof whereby it may swing out of the way of the supplemental frame on the turning of the latter, a second plate hingedly attached to the main frame at the bottom thereof and lying normally horizontal to have its free edge engage the supplemental frame at the bottom thereof whereby turning movement of the supplemental frame is precluded except on raising the said plate to swing outwardly and upwardly from the main frame, and lateral movable plates mounted on the supplemental frame and engageable with side slots in the main frame, in the manner and for the purpose specified.

In testimony whereof I affix my signature.

ALICE P. McCCLAIR.
